UNITED STATES PATENT OFFICE.

ARTHUR H. ADAMS, OF ANTWERP, BELGIUM, ASSIGNOR TO WESTERN ELECTRIC COMPANY, OF CHICAGO, ILLINOIS, A CORPORATION OF ILLINOIS.

DESIGNATION-PLUG FOR TELEPHONE-SWITCHBOARDS.

No. 875,882.

Specification of Letters Patent.

Patented Jan. 7, 1908.

Application filed May 31, 1907. Serial No. 376,684.

To all whom it may concern:

Be it known that I, ARTHUR H. ADAMS, citizen of the United States, residing at Antwerp, in the country of Belgium, have 5 invented a certain new and useful Improvement in Designation-Plugs for Telephone-Switchboards, of which the following is a full, clear, concise, and exact description.

My invention relates to designation plugs 10 or plates for telephone switchboards, and its object is to provide a plug which is of simple construction, which can be readily inserted in or removed from a jack, and which, when in position, will be flush with the surface of 15 the strip of jacks.

Plugs or plates are commonly used in multiple jacks of telephone switchboards for designation purposes. For example, if service to a particular subscriber is discontinued, a plug is inserted in the multiple 20 jacks of his line as an indication of the fact to the operator. Such a plug, by its color, or by some mark it may bear, is used to indicate various conditions. Heretofore such 25 plugs have ordinarily been constructed so as to project in front of the strip in order that they might be readily grasped and thus easily removed. By my invention the feature of accessibility for removal purpose 30 is retained, whether or not the plug projects outward, and the withdrawal of said plug greatly facilitated.

My invention consists in so shaping the inner end of the plug that when inserted in 35 one position it is securely held in place, and when slightly turned it is released and may be readily withdrawn.

My invention may be more readily understood by reference to the accompanying 40 drawing, in which,

Figure 1 is a front fragmentary view of a strip of jacks showing designation plugs in position; Fig. 2 is a vertical section through one of the jacks, showing the manner in 45 which the plug is held in place. Fig. 3 is a view somewhat similar to that of Fig. 2, but showing the manner in which the plug is released; Fig. 4 is a perspective view of the plug of my invention; and Fig. 5 is a view 50 similar to Fig. 2, of a modified form of plug.

The plug 1 may be provided with a head 2 similar to the ordinary slotted head of a screw. The other end of the plug is cut away on one side to provide a flat surface 3. Dia- 55 metrically opposite the surface 3 the plug is

beveled towards its tip to produce a cam surface 4.

To insert the plug 1 in a jack 5, it is merely pushed therein, the spring 6 engaging the flat surface 3, and securely holding the plug 60 or plate with its front face flush with the face of the strip, as indicated in Fig. 2. To remove the plug 1 it is merely necessary to rotate the same one-half of a revolution, bringing the beveled surface 4 beneath the spring 65 6. Said spring, by its resiliency, then pushes the plug onward a slight distance, as indicated in Fig. 3, whereupon the plug may be readily grasped and withdrawn.

In Fig. 5 I have shown a modified form of 70 plug in which the head 2 projects slightly beyond the face of the strip and in which the front end of the surface 3 is beveled in order that the spring 6 may more readily ride onto the flat surface 3. 75

Having described my invention, I claim:

1. The combination with a spring jack, of 80 a designation plug having a surface against which a spring of said jack is adapted to bear to hold said plug in place, and a cam surface adapted when the plug is turned from its inserted position to coöperate with said spring to release said plug.

2. The combination with a spring jack, of 85 a designation plug having a flat surface on one side against which a spring of said jack is adapted to bear to hold said plug in place, and a beveled surface upon its opposite side against which said spring is adapted to bear, upon the rotation of said plug from its in- 90 serted position.

3. A designation plug comprising a cylindrical body portion having one side cut away at its end to provide a flat surface, and having the opposing side beveled at the end of 95 the plug towards said flat surface.

4. A designation plug comprising a cylindrical body portion having a slotted head upon one end, said body portion being cut away at its opposite end upon one side to 100 form a flat surface, and having the opposite side beveled at the end of the plug.

In witness whereof, I, hereunto subscribe my name this fourteenth day of May A. D., 1907.

ARTHUR H. ADAMS.
